(57) **CLAIM**

The ornamental design for an elevated pet platform, as shown and described.

DESCRIPTION

FIG. 1 is a front isometric view of an elevated pet platform;

FIG. 2 is a front view thereof;

FIG. 3 is a back view thereof;

FIG. 4 is a top view thereof;

FIG. 5 is a bottom view thereof;

FIG. 6 is a right side view thereof, the left side view being a mirror image of the right side view;

FIG. 7 is a front isometric view a second embodiment of FIG. 1;

FIG. 8 is a front view of FIG. 7;

FIG. 9 is a back view of FIG. 7;

FIG. 10 is a top view of FIG. 7;

FIG. 11 is a bottom view of FIG. 7;

FIG. 12 is a right side view of FIG. 7, the left side view being a mirror image of the right side view;

FIG. 13 is a front isometric view a third embodiment of FIG. 1;

FIG. 14 is a front view of FIG. 13;

FIG. 15 is a back view of FIG. 13;

FIG. 16 is a top view of FIG. 13;

FIG. 17 is a bottom view of FIG. 13;

FIG. 18 is a right side view of FIG. 13, the left side view being a mirror image of the right side view;

FIG. 19 is a front isometric view a fourth embodiment of FIG. 1;

FIG. 20 is a front view of FIG. 19;

FIG. 21 is a back view of FIG. 19;

FIG. 22 is a top view of FIG. 19;

FIG. 23 is a bottom view of FIG. 19; and,

FIG. 24 is a right side view of FIG. 19, the left side view being a mirror image of the right side view.
